CLAIM

The ornamental design for a baffle for a light fixture, as shown and described.

DESCRIPTION

FIG. 1 is a bottom plan view of the baffle;
 FIG. 2 is a bottom isometric view of the baffle of FIG. 1;
 FIG. 3 is a front elevation view of the baffle of FIG. 1;
 FIG. 4 is a rear elevation view of the baffle of FIG. 1;
 FIG. 5 is a left side elevation view of the baffle of FIG. 1;
 FIG. 6 is a right side elevation view of the baffle of FIG. 1;
 FIG. 7 is a top plan view of the baffle of FIG. 1;
 FIG. 8 is a top isometric view of the baffle of FIG. 1; and,
 FIG. 9 is a cross-sectional plan view of the baffle of FIG. 1 taken along line 9-9 of FIG. 3.

The broken lines in the drawings illustrate portions of the baffle for a light fixture which forms no part of the claimed design.
